UNITED STATES PATENT OFFICE

HANS KNÖRER, OF NUREMBERG, GERMANY, ASSIGNOR TO THE FIRM A. W. FABER
CASTELL-BLEISTIFT-FABRIK A.-G., OF STEIN, NEAR NUREMBERG, GERMANY

PACKING CONTAINER

Application filed April 4, 1929, Serial No. 352,553, and in Germany June 21, 1928.

This invention relates to packing containers for lead and coloured pencils, writing materials or other articles, which differ from containers of a known kind in this, that they 5 comprise an inner box adapted to the kind of articles to be packed in them, which are provided with a fancy enclosure forming a toy figure, so that the container serves two purposes, acting both as a container for the 10 articles and as a toy. A flat rectangular inner box with a projecting edge is particularly suitable for adaptation as a toy, as the broad walls of the box may suitably be used as supports for lining or enveloping parts which 15 determine the external shape of the toy figure. The enveloping parts consist for instance of two stamped out pieces of cardboard corresponding to the contour lines of the toy to be represented, the edges of the surfaces of 20 which are connected by a transverse wall, so that the finished packing container produces the impression of a flat-end wooden figure. The cardboard pieces may either be fixed, for instance by an adhesive, to the broad sides of 25 the inner box or may themselves form the walls of the box. In the latter case a cardboard strip inserted vertically between the two pieces of cardboard acts as a bounding wall for the space for the reception of the 30 articles.

The longitudinal axis of the inner box may be parallel, at an inclination to, or perpendicular to the longitudinal direction of the toy figure. The cross-sectional shape of the 35 inner box may instead of being rectangular be round, oval, polygonal or any other shape. The most suitable forms for the toy figure are those representing human beings or animals.

40 In the accompanying drawings a constructional example of the invention is shown, Fig. 1 being a longitudinal section through the still uncovered packing container on line A—A of Fig. 3,

45 Fig. 2 a longitudinal section on line B—B of Fig. 3,

Fig. 3 a cross-section on line C—C of Fig. 1,

Fig. 4 a perspective view of the finished packing container and

50 Fig. 5 a detail to an enlarged scale.

The packing container consists of a flat, rectangular inner box which is formed in a known manner of the upper side 1 and the lower side 2 with the inserted box neck 3 and of a fancy envelope 4 (Fig. 4) which also 55 consists of an upper and a lower part, the joint between the upper and lower side of the inner box lying in the same plane as the joint 4a between the upper and lower part of the envelope. The inner box serves as a 60 receptacle for the articles to be packed, for instance the lead pencils 5 (Fig. 3).

The packing container is made in the following way: First of all the inner box is made, the narrow and broad walls 6, 7, 8 and 65 9 of which are creased and bent from a single piece of cardboard and are connected together at the abutting longitudinal edges by a paper strip 10 (Fig. 5). The upper and lower end walls 11 and 12 are glued in so as 70 to be flush. The box neck 3 is stuck in in a known manner into the lower wall 2. After the inner box has been completely made, the parts of the figure in the form of flat pieces 13 and 14 of cardboard or the like are glued 75 on to the two broad side walls 6 and 8, the contours of the said envelope being stamped out to represent a toy figure. The parts of these cardboard pieces projecting beyond the upper end of the inner box are accurately 80 kept apart at the required distance from one another by a reinforcing strip 15 bent in the form of a U, so that the marginal edges of the pieces of cardboard are equidistant from one another over their entire contour line. 85 The narrow marginal surfaces 16 and 17 of the pieces of cardboard are thereupon connected together along their periphery by a cardboard strip 18. The cardboard framework thus made is thereupon covered with 90 coloured printed paper bearing pictorial representations. The printed sheets of paper 19, 20 correspond in shape to the pieces of cardboard, but are made slightly larger, so that, when being stuck on, the edges 19a and 20a can be bent over, so that a tidy edge is 95 obtained. The transverse wall 18 which is not yet covered can then be covered by a suitably printed paper strip 21 which covers the edges 19a and 20a. The whole of the 100

envelope comprising the cardboard framework 13, 14, 18, and its paper covering is cut through to form a joint 4a at the same level as the joint between the upper and lower parts 5 of the inner box.

Both pieces of cardboard or only one may of course be covered with paper bearing pictorial representations, the other piece of cardboard being in the latter case covered with 10 white or single-coloured paper. The new packing container, owing to its being made in the form of a standing figure, is particularly suitable for shop-window advertising purposes. For special cheap advertising containers or toys the packing container may be so constructed that only one broad side 15 of the box containing the goods is provided with a piece of cardboard representing the toy. The inner box may be made in the 20 form of a box with a slip on, sliding or hinged lid. In the first case the joint of the two parts of the box or envelope will be a short distance above the base surface. When made in the form of a box with a sliding lid, 25 the envelope will have no joint. The pieces of cardboard will then extend straight through to the bottom and the lower part of the box have an end surface corresponding in size to the base surface of the toy. 30 When a box with a hinged lid is to be used as the container a part of the piece of cardboard must be made in the form of a flap.

What I claim is:

1. A packing container for lead and coloured pencils and other articles in the form 35 of a toy figure which is capable of being placed in an erect position, comprising in combination a flat inner box in two parts, two pieces of card formed to correspond to 40 the outline of the desired toy figure, secured to the broad sides of the box, and a strip of card joining the edges of the two pieces of card and surrounding the box, the strip and the two pieces of card being cut at the point 45 where the inner box is divided.

2. A packing container for lead and coloured pencils and other articles in the form 50 of a toy figure which is capable of being placed in an erect position, as claimed in claim 1 in which the inner box is of rectangular shape.

3. A packing container for lead and coloured pencils and other articles in the form 55 of a toy figure which is capable of being placed in an erect position, comprising in combination a flat inner box in two parts disposed one above the other, two pieces of card formed to correspond to the outline of the desired toy figure one secured to the front 60 and the other to the back of the box, and a strip of card joining the edges of the two pieces of card and surrounding the box, the strip and the two pieces of card being cut at the point where the inner box is divided.

4. A packing container for lead and col-

oured pencils and other articles in the form 70 of a toy figure which is capable of being placed in an erect position, comprising in combination a flat inner box in two parts disposed one above the other, an inserted box neck, and an outer envelope, also in two parts, consisting of two pieces of card, both of the same shape, formed to correspond to 75 the outline of the desired toy figure and secured to the back and front of the box and a strip of card joining the edges of the two pieces of card and surrounding the inner box, the joint between the upper and lower parts of the box lying in the same place as the joint between the upper and lower parts 80 of the outer envelope.

In testimony whereof I have signed my name to this specification.

HANS KNÖRER.
